Fig. 3

Fig. 1 is a side elevation view of a vehicle showing my new design; the opposite side of the vehicle presenting the same appearance.

Fig. 2 is a perspective view of the vehicle, looking forwardly from the rear.

Fig. 3 is a somewhat enlarged sectional plan view taken on line 3—3 of Fig. 1.

In the above views, the dominant features of the design are shown in full lines.

I claim:

The ornamental design for a vehicle, as shown and described.
